UNITED STATES PATENT OFFICE.

ANDREW O. PETERSON, OF SANTA BARBARA, CALIFORNIA.

VEHICLE-OPERATED SWITCH.

Application filed March 23, 1927. Serial No. 177,820.

This invention relates to electrical apparatus, and more particularly to a single operated switch for use in garages and the like.

In private garages adjoining residences, there is usually a wall switch of the conventional type for operating the lights of the garage, and when the driver of a vehicle enters the garage in the dark, he is obliged to locate this switch by striking a match or 10 by groping for the same in the dark. In order to remove his automobile from the garage it is often necessary for him to turn the lights on when he locates the switch, drive his car from the garage and then 15 return to the garage to turn the switch off before he closes the doors. Similarly, on returning to the garage he must stop the car, enter the garage and turn the lights on, return to his car and drive the car within the 20 garage, then turn the lights off before leaving. This is quite troublesome operation, especially if the switch is located on the wall of the garage where he must feel for the same in the dark. Then, in order to overcome 25 this inconvenience, I have developed this particular invention.

It is an object therefore, of this invention to provide a switch that will enable the lights in the garage to be turned on and off 30 as the car leaves or enters the garage without requiring the driver to leave his position at the steering-wheel.

It is a further object of this invention to provide a switch located on the ground, 35 so that the driver may merely pass over the switch with the vehicle and operate the same either to turn the lights on or turn the lights off.

A still further object of this invention is to 40 provide a switch which is comparatively inexpensive to manufacture, which is strong and durable, which will not get out of order due to heavy pressures exerted upon the same, which is efficient in its operation and well adapted to perform the services required of it.

In the accompanying drawings forming a part of this specification,

Figure 1 is a diagrammatic view showing 50 the position of my improved switch with respect to the path of the vehicle and the garage in which the vehicle is housed.

Figure 2 is a longitudinal, vertical, sec-

tional view of my switch assembly, showing the operative parts thereof. 55

Figure 3 is a transverse, vertical, sectional view, the plane of section being indicated by the line 3—3 of Figure 2.

Figure 4 is a diagrammatic view of the electrical connections which co-operate to 60 make up my invention.

In the above drawings, like characters of reference designate like elements throughout. The reference numeral 1 designates a garage or building in which a vehicle may 65 be stored. The reference numeral 2 designates the drive-way or path in which a vehicle must travel in order to enter the garage 1.

My invention is designated as an entirety 70 at 3, and comprises certain mechanical elements which are adapted to be embedded beneath the surface of the drive-way so that the actual operating means rests substantially on the surface of the ground. My 75 invention includes a substantially cup-shaped container 4 sunk within a recess in the ground. The upper end of the container 4 extends a slight distance above the ground, and on either side of the same are stationary 80 supports 5 and 6. Securely fastened to these supports 5 and 6 by means of bolts, rivets or the like, are a pair of spring-arms 7 and 8, which arms are the actual operating elements of my device. Their operation will 85 be described in detail at a point later in this specification.

A plate 9, bolted to the upper end of the container as at 10, completely covers the same and extends partially over the supports 90 5 and 6, and is bolted at its outer marginal edges to these supports by the same means whereby the spring arms 7 and 8 are bolted thereto. Fastened to each of the spring arms are the plungers 11 and 12 respectively, 95 which extend through the plate 9 into a container, and at their lower ends make contact with the push-buttons 13 and 14 that serve to operate the conventional type of switch 15, which switch makes operative electrical 100 connections with the garage lights by means of the conductors 16. A rectangular casing 17 extends downwardly into the container and is supported at its lower end on the frame 18 resting on the switch 15. Pivoted 105 to the outside of this container is a shield-

shaped plate 20 having cam surfaces 21 and 22 thereon. A slot 23 is provided in the casing 17 and lugs 24 and 25 extend outwardly through this slot and contact with the cam surfaces on the shield-like plate. A bracket is pivoted to the casing at 26 and is connected to the lower end of the shield as at 27 by means of a spring 28, which spring is in effect, a compression spring.

10 In actual operation, downward pressure on the arm 8 will cause the shield to swing on its pivot point to a symmetrical position with respect to the casing on the opposite side of the container 4. The plunger 11 will 15 depress the push-button 13 while the push-button 14 will be elevated and the arm 7 will assume the same position as the arm 8 originally assumed. The driver of the vehicle, on entering his garage, causes the wheel of 20 his vehicle to depress the arm 8 so that the lights will be turned on and it will not be necessary for him to leave his vehicle to search for a switch-button placed on the wall. On leaving his garage, in order to 25 turn the lights off, he may run his vehicle over the arm 7, thereby depressing the same and operating the switch. If he is leaving the garage on foot, it is merely necessary for him to step on the arm 7 to turn off 30 the lights, or on entering the garage on foot he may step on the arm 8 to turn on the lights. In either event, whether the lights are to be turned on or off, the desired change may be effected by depressing whichever arm 35 is in its elevated position. This feature obviates the necessity of marking the arms or of remembering which one must be actuated to complete the circuit, and which to break it. The coil-spring 28 should be constructed 40 so as to have sufficient strength so that stray animals or children will not accidentally turn on the lights. When the plate 20 has its symmetrical axis vertical, the plate is unstable and will not remain in such a position. 45 The plate at all times will rest at an inclination to the left or to the right of the container, as its center of buoyancy is located at a point beneath its center of inertia.

I do not desire to limit myself to the exact 50 arrangement of parts shown or described in this specification and its accompanying drawings. Other modes of applying the principle of this invention may be employed instead of the one explained. Various 55 changes may be made as regards the mechanism herein disclosed, providing the means covered by any one of the following claims be employed.

What I claim and desire to secure by Letters Patent is:

60 1. A switch comprising in combination a container adapted to be embedded in the ground in the path of travel of a vehicle, a tubular casing within said container, a switch upon which said casing is supported,

having reciprocal push-buttons for making and breaking an electrical circuit respectively, a pair of rods extending downwardly through said casing, contacting with said push-buttons, a pair of horizontal arms 70 above said container contacting with said rods whereby a vehicle may selectively be pressed by virtue of its weight, said rods to operate said switch.

2. A switch comprising in combination a 75 container, means in said container for making and breaking an electrical circuit comprising a pair of reciprocal push-buttons, a pair of rods extending upwardly from said push-buttons to a point outside of said container, a plate pivoted within said container, projections on said rods engaging cam surfaces on said plate, and a coil-spring attached to said plate to impart to 80 the same a degree of instability whereby 85 said reciprocal push-buttons will be either elevated or depressed, and means whereby the weight of a vehicle may be imparted to either of said rods to operate said switch.

3. A switch comprising a container adapted to be positioned in the path of travel of a vehicle, a switch positioned within said container, said switch comprising a pair of push buttons adapted to be selectively operated to make or break an electrical circuit, a rod associated with each of said buttons and slidably mounted within the container, and an arm operatively connected to each rod, said arms being positioned closely adjacent the surface over which the vehicle 100 travels.

4. A switch comprising a container adapted to be positioned in the path of travel of a vehicle, a switch positioned within said container, said switch comprising a pair of 105 push buttons adapted to be selectively operated to make or break an electrical circuit, a rod associated with each of said buttons and slidably mounted within the container, and an arm operatively connected to each rod, said arms being positioned closely adjacent the surface over which the vehicle 110 travels, and extending from opposite sides of the container.

5. A switch comprising a container adapted to be positioned in the path of travel of a vehicle, a switch positioned within said container, said switch comprising a pair of push buttons adapted to be selectively operated to make or break an electrical circuit, 115 a rod associated with each of said buttons and slidably mounted within the container, means for automatically extending one rod when the other is retracted, and an arm operatively connected to each rod, said arms 120 being positioned closely adjacent the surface over which the vehicle travels.

6. A switch comprising a container adapted to be positioned in the path of travel of a vehicle, a switch positioned within said 125

container, said switch comprising a pair of push buttons adapted to be selectively operated to make or break an electrical circuit, a rod associated with each of said buttons and 5 slidably mounted within the container, a shoulder on each rod, a rocker plate pivoted between said rods and in engagement with both shoulders, a spring pivoted at one end

between said rods and at the other end to said plate, and an arm operatively connected to 10 each rod, said arms being positioned closely adjacent the surface over which the vehicle travels.

In testimony whereof I have signed my name to this specification.

ANDREW O. PETERSON.
